(57) CLAIM

The ornamental design for a pillow, as shown and described.

DESCRIPTION

FIG. 1 is a perspective view of a pillow of the present invention;

FIG. 2 is a front view of the pillow of FIG. 1;

FIG. 3 is a back view of the pillow of FIG. 1;

FIG. 4 is a right side view of the pillow of FIG. 1;

FIG. 5 is a left side view of the pillow of FIG. 1;

FIG. 6 is a top view of the pillow of FIG. 1;

FIG. 7 is a bottom view of the pillow of FIG. 1; and,

FIG. 8 is a perspective view of the pillow of FIG. 1 shown in use. The broken line showing of the person is for illustrative purposes only and forms no part of the claimed design.
